CLAIM

The ornamental design for a treat dispensing toy for pets as shown and described.

DESCRIPTION

FIG. 1 is an upper front right perspective view of a first embodiment of the treat dispensing toy for pets showing our new design.

FIG. 2 is a front elevation view thereof.

FIG. 3 is a right side view thereof.

FIG. 4 is a rear elevation view thereof.

FIG. 5 is a left side view thereof.

FIG. 6 is a top plan view thereof.

FIG. 7 is an upper front right perspective view of a second embodiment of the treat dispensing toy for pets showing our new design.

FIG. 8 is a front elevation view thereof.

FIG. 9 is a right side view thereof.

FIG. 10 is a rear elevation view thereof.

FIG. 11 is a left side view thereof.

FIG. 12 is a top plan view thereof.

FIG. 13 is an upper front right perspective view of a third embodiment of the treat dispensing toy for pets showing our new design.

FIG. 14 is a front elevation view thereof.

FIG. 15 is a right side view thereof.

FIG. 16 is a rear elevation view thereof.

FIG. 17 is a left side view thereof; and,

FIG. 18 is a top plan view thereof.

The dashed lines shown in the drawings are for purposes of illustrating portions of the article that form no part of the claimed design.
